UNITED STATES PATENT OFFICE.

WALTER FRENZ, OF BROOKLYN, NEW YORK, ASSIGNOR TO NEW YORK BUTTON WORKS,
OF NEW YORK, N. Y., A CORPORATION OF NEW YORK.

DESIGN FOR A BUTTON.

43,719.

Specification for Design.

Patented Mar. 18, 1913.

Application filed December 27, 1912. Serial No. 738,961. Term of patent 3½ years.

To all whom it may concern:

Be it known that I, WALTER FRENZ, a citizen of the United States, residing at Brooklyn, county of Kings, State of New York, have invented a new, original, and ornamental Design for Buttons, of which the following is a specification, reference being had to the accompanying drawing, forming a part hereof.

Figure 1 is a plan view of a button embodying my invention, and Fig. 2 is a view in elevation thereof.

I claim:

The ornamental design for a button, substantially as shown.

WALTER FRENZ.
